US0D1013530S

(12) **United States Design Patent** (10) **Patent No.:** **US D1,013,530 S**
(45) **Date of Patent:** **** Feb. 6, 2024**

(54) **CONTAINER**

(71) Applicant: **ZHEJIANG YIGE ENTERPRISE MANAGEMENT GROUP CO., LTD.**,
Zhejiang (CN)

(72) Inventor: **Dayong Zhang**, Zhejiang (CN)

(73) Assignee: **Zhejiang Yige Enterprise Management Group Co., Ltd.**,
Hangzhou (CN)

(**) Term: **15 Years**

(21) Appl. No.: **29/836,359**

(22) Filed: **Apr. 26, 2022**

(30) **Foreign Application Priority Data**

Oct. 26, 2021 (CN) 202130702604.1

(51) **LOC (14) Cl.** **09-01**

(52) **U.S. Cl.**

USPC **D9/663; D6/542**

(57) **CLAIM**

I claim the ornamental design for a container, as shown and described.

DESCRIPTION

FIG. 1 is a perspective view of a container, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
